ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,244,999.

Specification of Letters Patent. Patented Oct. 30, 1917.

Application filed November 29, 1915. Serial No. 64,060.

To all whom it may concern:

Be it known that I, ALBEN E. LUNDELL, a citizen of the United States, residing at New York, in the county of Bronx and State 5 of New York, have invented certain new and useful Improvements in Telephone-Exchange Systems, of which the following is a full, clear, concise, and exact description.

This invention relates to telephone exchange systems and more particularly to 10 signaling systems for telephone exchanges.

It is the object of this invention to provide an improved signaling arrangement operable upon the establishment of a connection 15 between a calling line and one of a plurality of classes of called lines, means being provided for releasing the arrangement upon the signaling of a called line belonging to either class.

According to the main feature of this invention, if a connection is established between a calling line and a called line of a certain class (e. g. a line leading to an operator's position), the signaling apparatus, 25 which was actuated upon the completion of the connection, is automatically restored upon the actuation of a signal associated with the called line.

The drawing represents a telephone exchange system embodying the features of 30 the present invention.

The invention will be more readily understood from the following detailed description and the appended claims.

The subscriber located at substation 10, desiring to obtain a connection with a station 11, removes his receiver from the switch-hook for causing the displaying of a signal 12 in the well-known manner. A connecting operator inserts thereupon an answering plug 13 into an answering jack 14 for extinguishing signal 12 and for taking the orders of the calling subscriber. She then sets up the number of the desired party on 45 a well-known revertive impulse sender 15 for controlling selector switches 16 and 17 to select the desired line.

A sequence switch (not shown) associated with selector 16 controls springs 18, 19 and 50 20. During the setting of the selectors, this sequence switch is in position 11, and the extent of travel of the selector switches is controlled by the successive opening and closure of a contact 21 provided in a controlling circuit at sender 15, and a stepping

magnet 22 controls the stepping of the sender in accordance with impulses sent from the switches back to the sender. As such selector switches and their circuit arrangements are well known in the art, and 60 as they do not form a part of the present invention, their detailed description does not seem necessary. Sequence switch spring 20 controls the holding of the selected trunk during conversation. After the selector 65 switches have been set, the sequence switch is moved out of position 11 into position 14 for extending the calling to the called line through springs 18 and 19.

The signaling of the called subscriber's 70 station takes place now. Upon the setting of selector switches 16 and 17, a relay 22' becomes energized by current flowing through a circuit closed at a sequence switch contact 60 actuated upon the setting of the 75 selector switch 17. The operation of the sequence switch arranged to control the contact 60 is described in a patent to F. N. Reeves, No. 1,218,804. Upon energization, relay 22' closes a circuit from ground, 80 through its armature and front contact, and the windings of relays 23 and 24, to grounded battery. Only relay 24 becomes energized; a shunt being closed around the winding of relay 23. Relay 24 closes a signaling 85 circuit from ground through ringing current generator 25, interrupters 26 and 27, or from grounded battery, through interrupter 27', the winding of a marginal relay 28, the lower front contact and armature of relay 24, wiper 29 of connector switch 17, line conductor 30, the bell at substation 11, line conductor 31, brush 32' of connector 17, and the upper armature and front contact of relay 24, to ground. Relay 90 28 energizes only upon the removal of the receiver at the called station, and opens at its back contact the shunt around the winding of relay 23, which then becomes energized, short-circuits relay 24 and closes 95 a locking circuit for itself.

Upon the deenergization of relay 24, a circuit is closed from grounded battery, through the secondary winding of a repeating coil 32, the winding of a supervisory relay 33, the bottom contact of sequence switch spring 19, the called substation loop, the top contact of sequence switch spring 18, and the secondary winding of repeating coil 32, to ground. Relay 33 becomes energized 100 105 110

and causes in the well-known manner the actuation of a supervisory signal, indicating to the connecting operator that the desired station has answered.

5 If the calling station 10 desires to obtain a connection to a special operator whose telephone set is indicated at 34, the connecting operator will cause the setting of switches 16 and 17 in the same manner as 10 above described to select an outgoing line terminating in a jack 35 at the special operator's position. Upon the energization of 15 relay 24, a circuit is closed from the ringing current source through the winding of relay 28, the lower front contact and armature of relay 24, connector brush 29, conductor 36, condenser 37, the left-hand winding of a relay 38, conductor 39, connector brush 32', and the upper armature and front contact 20 of relay 24, to ground. The left-hand winding of relay 38 is responsive to alternating current, whereby armature 40 will be attracted. Armature 41 controlled by the 25 right-hand winding of relay 38 is released and a circuit is closed from ground through 41, contact 42, the winding of a relay 43, a lamp signal 44, and the winding of relay 45, to grounded battery. Relays 43 and 45 and lamp 44 will be actuated, and relay 45 30 closes a circuit for an audible signal 45', whereby the special operator will be informed that a call is awaiting attention.

The above described signaling circuit, including the winding of relay 28, does not 35 permit the passage of sufficient current for energizing this relay. In order, however, to make possible the tripping of the ringing, *i. e.* the opening of the signaling circuit immediately upon the setting of the 40 selector switches, a circuit is closed from grounded battery, through conductor 46, the armature and front contact of relay 43, resistance 46', conductor 36, connector brush 29, the lower armature and front contact 45 of relay 24, and the winding of relay 28, to the ringing current source. Relay 28 becomes energized and opens the signaling 50 circuit in the above described manner. Relay 33 controlling the supervisory signal, however, will not be energized, due to the closure of a shunt around its winding 55 through conductor 46. It should be mentioned at this point that the tripping battery connected to the interrupter 27' is of greater voltage than the battery connected to the repeating coil 32.

As soon as the special operator inserts her plug 47 into jack 35, a circuit is closed from grounded battery, through resistance 59 48, the sleeve contacts of plug 47 and jack 35, and the right-hand winding of relay 38, to ground. Relay 38 attracts its armature 64, opening thereby the circuit of relays 43 and 45, and lamp 44. Relay 43 opens the shunt around the windings of relay 33, and

this relay becomes energized and actuates the supervisory signal to the connecting operator's position. The circuit for relay 33 extends from grounded battery, through 33, 19, 29, 36, resistances 46' and 49, the tip 70 contacts of jack 35, and plug 47, and the primary winding of a repeating coil 50 to ground.

The special operator by depressing her listening key 51 may connect in circuit her 75 telephone set 34 to converse with the calling subscriber.

The release of the apparatus employed in the extension of calls to subscribers' lines or operators' positions may be controlled in 80 any well-known manner.

What is claimed is:

1. In a telephone exchange system, an incoming and an outgoing line, means for establishing a connection between said lines, a 85 signaling circuit closed upon the establishment of said connection, a signal in said circuit associated with the outgoing line, a relay in said circuit actuated in response to the operation of said signal, and means operative thereupon for rendering said circuit ineffective.

2. In a telephone exchange system, a plurality of lines, means for establishing a connection between calling and called lines, a 95 signaling circuit closed upon the establishment of said connection, a signal in said circuit associated with said called line, a relay in said circuit energized in response to the actuation of said signal, and means operative 100 thereupon for opening said circuit.

3. In a telephone exchange system, incoming lines and a plurality of classes of outgoing lines, means for establishing a connection between a calling incoming and a called outgoing line, a signaling circuit closed upon the establishment of said connection, a relay associated with each of said incoming lines, a signal associated with each of said outgoing lines, a manually operable switch 105 associated with each outgoing line belonging to one class, means operative upon the establishment of a connection for closing a signaling circuit including the relay associated with the calling incoming line and the 110 signal associated with the called outgoing line, means operative in response to the actuation of the switch of the called outgoing line for energizing said relay, means responsive to the actuation of a signal associated with the outgoing line belonging to 115 another class for energizing said relay, and means operative upon the energization of said relay for opening said circuit.

4. In a telephone exchange system, a plurality of lines, means for establishing a connection between a calling and a called line, a signaling circuit closed upon the establishment of said connection, a signal in said circuit associated with said called line, a mar- 125

ginal relay in said circuit prevented from being energized upon the closure thereof, and means operative in response to the actuation of said signal for permitting the energization 5 of said marginal relay.

5. In a telephone exchange system, incoming lines and a plurality of classes of outgoing lines, means for establishing a connection between a calling incoming and a called outgoing line, a signaling circuit closed upon the establishment of said connection, a marginal relay associated with each of said incoming lines, a signal associated with each of the outgoing lines, a manually operable switch 10 associated with each of the outgoing lines belonging to one class, means operative upon the establishment of a connection for closing the signaling circuit including the relay associated with the calling incoming line and the signal associated with the called outgoing line, said relay being prevented from 15 energizing upon the closure of said circuit, means operative in response to the actuation of said switch for permitting the energization of said relay, means responsive to the actuation of a signal associated with an outgoing line belonging to another class for permitting the energization of said relay, and means operative upon the energization 20 of said relay for opening said signaling circuit.

6. In a telephone exchange system, an incoming line and an outgoing line, means for interconnecting said lines, a relay associated 25 with the incoming line, a signal associated with the outgoing line, a circuit extending from the free pole of a relatively high voltage grounded battery through said relay and signal to ground, closed upon the establish-

ment of said connection, a relatively low 40 voltage grounded battery, and means controlled by said signal for connecting the free pole of said last mentioned battery to said circuit.

7. In a telephone exchange system, an incoming and an outgoing line, means for interconnecting said lines, a marginal relay associated with the incoming line and a signal associated with the outgoing line, a relatively high resistance circuit extending from the 45 free pole of a relatively high voltage grounded battery through said relay and signal to ground, closed upon the establishment of said connection, a relatively low voltage battery, and means operable in response to the actuation of said signal for closing a relatively low 50 resistance circuit from the free pole of said relatively high voltage battery through the winding of said relay to the free pole of said relatively low voltage battery. 55

8. In a telephone exchange system, a plurality of lines, means for establishing a connection between a calling and a called line, signaling apparatus actuated upon the establishment of said connection, a relay controlled thereby, a called station from which said relay may be controlled, a signal controlled by said relay, means operable upon the actuation of said relay under the control of said apparatus for actuating said signal 60 and restoring said apparatus, and means operable upon the actuation of said relay under the control of said station for restoring said signal. 65

In witness whereof I hereunto subscribe 70 my name this 27th day of November, A. D. 1915.

ALBEN E. LUNDELL.
